CUSHIONED SHOE

Nicholas Allaniello, Toronto, Ontario, Canada

Application December 20, 1948, Serial No. 66,167

5 Claims. (Cl. 36—28)

1

This invention relates to shoes and has for its principal object to provide a new and improved construction whereby sponge rubber cushioning means are incorporated in the sole and heel of the shoe in a novel manner to absorb the shocks and jars to which the foot and consequently the body of the wearer are subjected.

Although I am aware it is not broadly new to employ sponge rubber or other shock absorbing cushioning means in the construction of shoes, the manner in which it has heretofore been proposed to use such cushioning means is subject to the objection that the cushions frequently became displaced during usage and would become balled or rolled to form objectionable bulges.

Furthermore, the operation of fabricating the shoe has been complicated by the use of the sponge rubber or other cushioning means which tended to create an unwieldy bulge around the marginal edges of the shoe where it is necessary to sew the welt to the insoles and to the uppers of the shoe.

Another object of the present invention is to provide a new and improved construction that will obviate the objectionable features above referred to and to provide a new and improved construction by means of which the manufacturing operations will be markedly simplified.

A further object is to provide a new and improved construction for a shoe which has incorporated therewith foam or sponge rubber cushion inserts which are associated with a relatively stiff sole leather insole and in such a manner as to provide cushioning means under the ball of the foot and heel of the wearer where cushioning means are most needed to absorb shocks to which the foot is subjected.

Another object is to provide a shoe construction comprising a relatively stiff leather insole provided with cut-out portions or sockets in which the sponge rubber cushioning means are inserted and securely fastened so as to prevent relative movement between the cushioning means and insole during customary usage.

As it is highly important when sponge or foam rubber cushioning means are employed in the construction of a shoe to prevent any seepage of water into the sponge rubber cushions which tend to retain the water in the interstices of the sponge rubber, it is another object of the present invention to provide a new and improved storm welt construction that will entirely obviate any seepage of water between the uppers and soles of the shoe and thence into the sponge rubber inserts.

A further object of the invention is to incor-

2

porate an arch-grip or support as a part of the shoe as originally constructed.

The above and other objects of the invention will appear more fully from the following more detailed description and by reference to the accompanying drawing forming a part hereof and wherein

Fig. 1 is a central longitudinal section of a shoe constructed in accordance with the principles of the present invention;

Figs. 2, 3 and 4 are vertical cross sections taken on the lines 2—2, 3—3 and 4—4 looking in the direction of the arrows appearing at the ends of said section lines.

15 As shown in the drawing, the numeral 10 indicates an insole of relatively stiff sole leather which extends from a point adjacent the front to a point adjacent the rear part of the shoe. As the first step in constructing the shoe, this 20 insole 10 is cut away at the heel portion thereof to provide a shelf-like portion 11 bounded by a vertical shoulder 12 (see Figs. 1 and 4). A cushion or pad 13, preferably of sponge or foam rubber, has its marginal edges resting upon the shelf 11 and confined against lateral movement by the shoulder 12, the sponge rubber pad being securely cemented to the shelf 11 and shoulder 12. Immediately underneath the major central part of the sponge rubber pad 13 the insole is preferably cut 25 out to provide a hole as indicated at 14 (Figs. 1 and 2). This hole, after the sponge rubber cushion has been inserted and cemented in place, is preferably filled with a layer of cork 16 which can be either in the form of a sheet of cork or 30 a powdered cork filler that can be applied in paste form while hot and cemented or otherwise 35 securely fastened to the underface of the sponge rubber cushion.

Immediately under the ball portion of the 40 wearer's foot, the leather insole is also cut away to provide a shelf 17 and shoulder 18 similar to the shelf and shoulder 11 and 12, a cushion 19 also preferably of sponge rubber being placed upon the shelf 17 and cemented to said shelf 45 and shoulder 18 in the same manner as described in connection with the cushion 13. The insole immediately under the major portion of the cushion 19 is also cut away, as indicated at 20, to form a hole which is filled with a cork insert 21 similar to the insert 16 and which is securely cemented 50 to the underface of the cushion 19.

After the insole 10 has been cut away to form the shelves and shoulders 11, 17 and 12, 18, respectively, the cushions 13 and 19 have been securely cemented in place and the cork inserts

also being placed within the holes 14 and 20 and likewise cemented to the underface of the cushions 13 and 19, the insole 10 then forms a complete assembly. An innermost sole, or sock lining, 21 of soft leather, such, for example, as goatskin is next securely cemented on its underside to the top of the insole assembly with the edge of the inner sole lapped around and completely covering the entire marginal edge of the stiff leather insole assembly as indicated at 28.

A storm welt is next prepared by folding a piece of soft leather 22, such, for example, as the type of leather used for the shoe's uppers, about a piece of twine 23 or other suitable cordage. This storm welt comprising the strip of leather 22 with the cordage 23 confined at its outer edge is then sewn, preferably by hand, to the usual main welt 25 when the latter is sewn to the marginal portion of the stiff sole leather insole 10 and to the marginal lower portion of the vamp 30 by stitches 26, the storm welt 22, 23 being located on top of the main welt and being squeezed or compressed tightly by the stitches 26 between the marginal underside of the vamp 30 and the top face of the main welt 25 so as to form a tight seal that is impervious to moisture and effectively prevents the entry or seepage of water into the inner sole and sponge rubber cushions 13 and 19. The main welt 25 is provided with the usual groove 25-a which serves as a guide for the location of the stitches 31 by means of which the outer sole 32 of the shoe is secured to the main welt 25 and thence through the stitches 26 to the vamp or upper of the shoe.

As will be seen from the foregoing, the foam rubber cushion pads 13 and 19 are localized immediately under the heel and under the ball of the wearer's foot; those portions which are subjected to the greatest shock in walking, the cork inserts 16 and 21, also serving to supplement the cushioning effect of the foam rubber cushions 13 and 19. The portion 10-a of the insole 10 that lies between the cushions 13 and 19 and is located immediately under the metatarsal arch is not provided with any cushioning means because in a normal foot this portion of the foot does not come into contact with the portion 10-a of the insole. The usual steel shank (not shown) may be provided between the outer sole 32 and insole 10 under the portion 10-a of the latter. As shown in Fig. 4, this portion of the insole is preferably extended as indicated at 10-b in Fig. 3 to form, what is known as, an arch grip to furnish support to the highest part of the metatarsal arch on the inner side thereof at the point where support is most needed for this portion of the foot.

As will be seen by reference to Figs. 1 and 2, a flat marginal ledge 33 approximately one-half inch in width extends around the ball and toe portion of the shoe and a similar flat ledge 34 also of a width of approximately one-half inch extends around the heel portion, thus obviating the objectional bulge or thickness that otherwise would be present if the sponge rubber cushion were extended entirely across and over the entire insole.

The cutting away of the stiff leather insole to provide the ledges 33 and 34 and bounding shoulder 12 upon which the cushions 13 and 19, respectively, are placed and held against lateral movement by the bounding shoulders 17 and 18, respectively, together with the cementing of the rubber cushions to the ledges and shoulders securely prevents any movement of the rubber cushionings from their proper positions beneath the heel and ball portions of the wearer's foot

when the shoe is in use. Likewise the covering of the entire insole assembly with the sock lining 21 and the cementing of the lower face of the latter to the rubber cushions and insole, together with the lapping of the marginal edge of the sock lining around the edge of the insole 10, which marginal edges are also securely cemented together also serves to hold the cushions securely in position. Furthermore, the cutting away of substantial portions of the stiff, relatively heavy leather insole and the use of the sponge rubber cushions and cork inserts in the cutaway portions of the shoe make the shoe much lighter in weight than if the entire insole were covered by a sponge rubber cushion.

My improved shoe construction as heretofore described may therefore be employed in shoes for women's evening wear in which all of the advantages of the use of sponge rubber cushions may be employed without making the shoes any heavier or more bulky than shoes of standard construction. The construction is also especially adapted for use in custom made ice skating boots, the foam rubber cushions being highly effective for absorbing the shocks to which the skater's foot is subjected when executing the various jumps which are performed by figure skaters and the light weight of the shoes being very desirable for figure ice skating boots.

In the fabrication of the insole assembly, the cork inserts are preferably made slightly thicker than that part of the insole which defines or bounds the apertures 14, 18 so that the inserts initially project slightly below the bottom surface of the insole. When, however, the stiff leather bottom outer sole is secured by means of the main welt 25 and stitches 31 to the insole, the cork inserts and cushioning pads 13 and 19 are forced upwardly and compressed upwardly to bring the lower surfaces of the cork inserts flush with the lower surface of the insole 10.

While I have described and illustrated a satisfactory and preferred constructional example, it will, of course, be understood that many changes, variations and modifications of the specific constructional example illustrated may be employed without departing from the spirit of the invention as set forth in the claims hereunto appended.

I claim:

1. In a shoe, a relatively stiff sole leather insole having the major portions thereof immediately under the ball and the heel of the wearer's foot cut away to form through apertures and a supporting ledge bounding each aperture, and resilient cushioning means supported on and securely cemented to said ledge.

2. In a shoe, a relatively stiff sole leather insole having the major portions thereof immediately under the ball and the heel of the wearer's foot cut away to form through apertures and a supporting ledge bounding each aperture, and resilient cushioning means supported on and securely cemented to said ledge and cork inserts filling said apertures below said cushioning means and being securely cemented to the undersurface thereof.

3. In a shoe, an insole assembly comprising a relatively stiff sole leather insole having a marginal border extending substantially horizontally inwardly from the entire peripheral edge thereof, a pair of resilient cushioning pads, one at the heel and the other at the ball portion of said insole and projecting above said marginal border, said insole being provided with apertures below

the major portions of said pads, cork inserts in said apertures integrally united to the underfaces of said pads and having their lower faces substantially flush with the lower surface of said insole, and a soft flexible leather sock lining covering the entire top face of said insole, said pads and said marginal border, and overlapping the periphery of said insole and being cemented thereto and to the top surface of said cushioning pads and insole.

4. In a shoe, an insole having a plane marginal substantially horizontal border extending inwardly from its entire periphery, a pair of recessed substantially horizontal supporting ledges extending inwardly from said marginal border and terminating at said border in a substantially vertical shoulder, one of the pair of said recessed ledges being located under the ball portion and the other under the heel portion of said insole, and resilient cushioning means seated upon said ledges and being securely cemented thereto and to said shoulders to prevent movement of said cushioning means relatively to said insole, said insole having a through aperture under the major part of each of said cushioning means and a cork insert filling said aperture, having its upper surface cemented to the undersurface of said cushioning means and having its undersurface substantially flush with the undersurface of said insoles.

5. In a shoe, an insole having a plane marginal substantially horizontal border extending inwardly from its entire periphery, a pair of recessed

substantially horizontal supporting ledges extending inwardly from said marginal border and terminating at said border in a substantially vertical shoulder, one of the pair of said recessed ledges being located under the ball portion of said insole, and resilient cushioning means seated upon said ledges and being securely cemented thereto and to said shoulders to prevent movement of said cushioning means relatively to said insole, said insole having a through aperture under the major part of each of said cushioning means, a cork insert filling said aperture having its upper surface cemented to the undersurface of said cushioning means and having its undersurface substantially flush with the underface of said insoles, and a soft flexible leather sock lining covering the entire top face of said insole, said pads and said marginal border, overlapping the periphery of said insole and being cemented thereto and to the top surface of said soft cushioning pads and insole.
